SURGICAL THERAPEUTIC APPLIANCE

Edward Sokolik, New Brighton, Minn.

Application May 6, 1946, Serial No. 667,515

29 Claims. (Cl. 128—240)

1
My present invention relates to improvements in therapeutic appliances and more particularly to those appliances that are used in treating diseased body lesions or cavities. It is employed to withdraw hemorrhages, suppurations, fetid air or gas out of body lesions or cavities, such as vaginal, prostatic, rectal, abdominal and the like, and then flush, disinfect and aerate such lesions or cavities of the body.

It is a principal object of this invention to provide a therapeutic appliance whereby therapy of diseased lesions or cavities is accomplished by first withdrawing hemorrhages, suppurations, fetid gas and the like, if any, and then bathing the lesions or cavities with therapeutic solutions and therapeutically processed air;

It is an important object of the invention to withdraw fluids from body lesions or cavities without injuring the tissues in the process of withdrawing the fluids;

It is a further object of this invention to provide a therapeutic appliance so constructed that it will flush, disinfect and aerate diseased lesions or cavities of the body with a minimum possibility of spreading the infection;

It is another object of the invention to provide in a therapeutic device compact means for simultaneously feeding into, and withdrawing fluids from lesions or cavities of the body;

It is still another object of this invention to provide in a therapeutic device means whereby the incoming and outgoing fluids used in the device for treating body lesions or cavities may be observed by the operator of the device;

It is a further object of this invention to provide in a therapeutic device means for supplying filtered, deodorized, sterilized and medicated air to the lesions or cavities of the body;

It is one object of this invention to provide a device whereby processed air can be used under atmospheric or generated air pressure;

Other objects of the invention are simplicity and economy of construction, ease and efficiency of operation, and adaptability to various uses.

Other objects and advantages will be apparent as the following specification progresses.

My invention is fully described in the following specification, of which the drawings accompanying same form a part, in which like characters with affix "a" in modifications refer to like parts in each of the views, and in which:

Fig. 1 is a schematic view of one embodiment of my invention showing the duplex receptacle for the therapeutic fluid medium and for suction inducing fluid medium in transverse perspective re-

spectively, the fluid feeding syringe with its cross-head fitting and the fluid suctioning and discharging artifice in vertical section, respectively.

Fig. 2 is an elevational view of the syringe showing the longitudinally corrugated surface thereof.

Fig. 3 is an elevational view of a modified form of the syringe in Figure 2 showing, partly in section, a plurality of superposed webs between each two adjacent corrugations, forming pockets for collecting fluids.

Fig. 4 is an elevation of an intermediate portion at one-eighth turn of the syringe shown in Figure 3.

Fig. 5 is a cross-section on line 5—5 of Fig. 4. Fig. 6 is a cross-section on line 6—6 of Fig. 4. Fig. 7 is a cross-section on line 7—7 of Fig. 4. Fig. 8 is a cross-section on line 8—8 of Fig. 4. Fig. 9 is a cross-section on line 9—9 of Fig. 2. Fig. 10 is a schematic view of a modified embodiment of the invention.

Fig. 11 is a cross-section on line 11—11 of Fig. 10.

Fig. 12 is a plan view, partly in section, of the air processor, the section being taken on the line 12—12 of Fig. 10.

Fig. 13 is a transverse view of the air processor on the line 13—13 of Figure 10.

Fig. 14 is a view of the air bulb with symbols for air checks, this structure to be interposed in the air supply conduit 62.

Referring to the drawings:

The numeral 16 designates in general the two-way syringe or nozzle 17 and two-way cross-head fitting 18 connected together. The syringe 17 and fitting 18 are made in two parts to permit quick disconnection for cleaning and sterilizing thereof, and for interchanging syringes adapted for specific uses. The fitting 18 is simple and streamlined to facilitate cleaning thereof. There are no parts which for obvious reasons are objectionable. The nipple 19 is the only appendix, and that can be molded integrally in the fitting.

The syringe 17 may be flexible or rigid, slender or broad, and of various shapes and lengths, depending on the anatomy of the organ or nature of the lesion to which therapy is to be applied. The connecting or open end thereof is transversely plane and the free end tapered to facilitate inserting thereof.

The generally adapted form of the syringe 17 is elongated and cylindrical, the surface thereof consisting of longitudinally extending corrugations or ridges 21 and channels or depressions 31, in alternate radial arrangement. While four

corrugations 21 and four channels 31 are shown, five of each might be preferable because five corrugations 21 could hold the tissues out of the channels 31 more effectively. Variations from two to six may be resorted to.

Formed in each of the corrugations 21 is a small fluid feeding inlet conduit 28, the top end of which is open and the bottom end closed. A large fluid withdrawing or outlet conduit 25 is axially formed in the syringe 17, the top end of which is open and the bottom end of which preferably has a small withdrawing or outlet orifice formed therein, to effectively withdraw all the fluid in the bottom of a cavity.

The object of the corrugations 21 and channels 31 is to contrive a novel arrangement adapted to feeding fluids into, and simultaneously withdrawing fluids from, lesions or cavities without injuring the tissues by the function of suctioning. The corrugations 21 are designed to form deep channels 31 there-between, and to afford stock in which to form fluid-feeding conduits 28, and which prevents tissues from bulging into the channels 31.

The object of the channels 31 is to collect fluids in lesions or cavities and vacate same, and to receive flushing fluids and simultaneously vacate same.

Each of the corrugations 21 has a plurality of spaced inlet orifices 30 in each of the opposed sides 29 thereof, communicating each inlet conduit 28 with the adjacent channel 31. The inlet orifices 30 are preferably angled to spray the flushing fluid into each channel 31 upwardly and outwardly to flush off the diseased tissues, which bear against the corrugations 21 and are exposed to the spraying solution.

From the apex of each of the channels 31 leads a plurality of spaced outlet orifices 26, which are formed in the body of the syringe 17, communicating each channel 31 with the fluid withdrawing conduit 25. It will be observed that both the inlet orifices 30 and outlet orifices 26 are in each channel 31, which arrangement is novel, whereby the fluids are vacated by suctioning, while the tissues are held back by the corrugations 21. The force of suction is satisfied by liquid, or air if there is no liquid, and not by the tissue. This principle could not prevail if the inlet orifices 30 and the outlet orifices 26 were in alternate arrangement in the channels 31. Inlet and outlet orifices 30 and 26, respectively, are disposed on the free end-portion of syringe 17 for obvious reasons.

The inlet orifices 30 have a combined cross-sectional area corresponding to the combined cross-sectional area of said fluid withdrawing or outlet orifices 26; and, the fluid feeding inlet conduits 28 have a combined cross-sectional area corresponding to the cross-sectional area of said fluid withdrawing or outlet conduit 25.

The syringe 17 is illustrated as having external screw-threads on the orificial end thereof, but a slip-joint connection would be suitable.

The cross-head fitting 18 comprises a fluid-feeding inlet tube 32 and a fluid-withdrawing outlet tube 33. The tube 32 is provided with internal screw-threads 24 in the ends thereof engaging the screw-threads of the nipple 19 in the intake end and screw-threads 22 of the nozzle 17. The tube 33 enters the tube 32 through the wall. It is integral with the tube 32 but does not need to be, and is projected out normally horizontally in the form of a short handle 34. The intake or internal end of the tube 33 is dis-

posed axially in the tube 32 and is adapted to connect with the outlet conduit 25 in the syringe 17 by abutting same. The tube 32 is in screw-threaded engagement with the screw-threaded intake end of the syringe 17, and is in communication with all the inlet conduits 28, which extend longitudinally in said nozzle 17. Surplus screw-threads 22 are provided on the intake end of the syringe 17 to insure a tight joint between the tube 32 and the outlet conduit 25. This joint could be of the telescopic type. The main body of the fitting 18 is made preferably of transparent material, such as glass or other material adapted to withstand sterilizing heat. The transparency of this fitting 18 with the transparent fluid conduit extension 34 is a novelty. It affords a means, whereby the incoming solution and outgoing fluid are observed to ascertain, when all the fluid has been withdrawn, what the pathological peculiarities thereof are, and also to aid in the focalizing of the syringe in the lesion, as the character of the outgoing fluid, if any, may indicate whether the syringe 17 is correctly focalized in the lesion or cavity. The extension 34 serves the dual function of focalizing the syringe 17 and of providing a transparent facility for visual observation of the outgoing fluids therethrough.

The modified syringe shown in Figs. 3, 4, 5, 6, 7 and 8 of the drawings is provided with a plurality of webs 31b spaced apart in each channel 31, and integral with the surface of the syringe 17, each forming a pocket. Each of the webs 31b has an edge corresponding to an arc to afford an edge more effectively to hold back, together with the corrugations 21, the tissues, and prevent same from bulging into the web pockets. Fig. 7 shows that each four webs 31b are circumferentially aligned, but this is just one form of arrangement, and dividing the free end-portion of the syringe 17 into separate portions.

Fig. 4 illustrates two adjacent corrugations 21 astride the channel 31 in which are a plurality of superposed webs 31b integral with the sides 29 of the corrugations 21. These webs 31b are sagged to form fluid collecting pockets. Adjacent each pocket, I provide an inlet orifice 30 from at least one of the inlet conduits 28 in the corrugations 21 and from the apex of each pocket into the outlet conduit 25, an outlet orifice 26. The incoming fluid from inlet orifices 30 sprays the tissue facing each pocket and flushes off the tissue, the flush being trapped in each pocket to prevent spreading of infection and withdrawn through the outlet 26 as fast as the flushing fluid is fed thereto. Each individual pocket has the cycle of therapy performed therein, and if a suppurating tissue is in contact with a particular pocket, the therapy is confined to that one pocket.

Fig. 10 is a modification of the apparatus comprising a simple receptacle 35 for therapeutic fluid medium, in communication with the injecting artifice 61, which includes the syringe 52 and cross-head fitting 57; an air processor 34b having portions shown in vertical section, in communication with the artifice 61; an electrically driven centrifugal pump 60 in communication with the artifice 61; and an air bulb shown in Fig. 14 which may be connected at 62 in communication with the air processor 34b and the artifice 61.

The air processor 34b should also be associated with the apparatus shown in Figure 1. A compressible pneumatic bulb shown in Figure 14 is interposed in an air inlet conduit 62 which communicates with the fluid conduits 40, 42a, or directly with the fitting 18 or 57 to cooperate with

the processor 34b, which provides processed air under atmospheric pressure only, while the bulb shown in Figure 14 provides generated-processed air by manual compression thereof to bathe under inflation the abdominal cavity through surgical opening, with therapeutic or processed air, after the fetid air or gases have been evacuated. This manner of therapy is beneficial to, and prevents such complications as, peritonitis, and the like.

The pneumatic bulb Fig. 16 is preferably provided with a pair of air check valves, a valve 62a on the intake end thereof and a valve 62b on the discharge end thereof. When the bulb is compressed the valve 62a checks the air from returning into the air processor 34 and is forced out thru the valve 62b and connections into the cavity being treated, and when the bulb is released the valve 62b checks the return into the bulb of the air from the cavity, and the valve 62a admits processed air into the bulb from the air processor 34 under atmospheric pressure.

The air processor 34b is used cooperatively with the reservoir 33 or 35 for therapeutic solutions to be fed into the lesions or cavities, and is in tubular communication with the cross-head fitting 57, and is interposed somewhere between the nipple 19 and the valve 37.

The essentials of the air processor are: a case 63 of suitable material which, of my preferred design, is cylindrical. A screw-threaded foraminous air-intake cover or cap 64, provided with a suspension eye 65, engages the top of the case 63. A conical air discharge chamber or funnel 66, provided with an air outlet spout, is formed integrally with the bottom of the case 63, but this funnel could also be in screw-threaded engagement with the case 63. Immediately subjacent to the cover 64 is a disk air-filtering member 67, and immediately above the funnel chamber 66 is a medically impregnated fumigating and filtering disk member 68 to medicate and sterilize and postfilter the outgoing air. Intermediate the members 67 and 68 are arranged a plurality, generally five, but three are shown as indicated by 69, of preferably cylindrical layers or sections of different odor or gas absorb or adsorb chemical agents. Each chemical agent is adapted to permit the air to pass or flow therethrough and to absorb and adsorb certain odors or gases, therewith more effectively, so that a combination of five agents 69 will absorb all odors or gases apt to be in the nonprocessed air.

Obviously the chemical agents 69 are readily removable from the case 63 for replacement and for re-activation thereof, such as charcoal, but in a small therapeutic air processor it is more expedient to replace the agents when more or less foully saturated.

The steps of processing the air are arranged in logical sequence. First, the air is filtered of all such impurities as dust, smoke, smoke grease, and the like by the air filtering member 67, through which it is forced by atmospheric pressure, then it is forced through the series of deodorizing agents 69. It will be observed that the air, now being filtered, will not plug the porous agents; the pores or foramen are always open and effectively permit the flowing of the filtered air therethrough. Finally, the filtered and deodorized air is forced through the medically impregnated member 68 to sterilize, and medicate the air as desired and to filter out oxides of the chemical agents. We now have a thoroughly therapeutic processed air.

The modified syringe combination artifice 61 includes a two-way syringe 52 and a transparent two-way cross-head fitting 57. The syringe 52 generally is adapted for deep canal service, such as prostatic therapy. It includes a pair of two-way conduits, an inlet conduit 53, with a plurality of inlet orifices 54, and an outlet conduit 55 with a plurality of outlet orifices 56. These conduits 53 and 55 are parallelly adjacent and separated by a wall extending longitudinally therebetween and defining longitudinally along each side of its ridge, recessed in between the said conduits 53 and 55, preferably a pair of deep channels 31a, one on each side of the wall. The inlet conduit 53 has at the lower end-portion a plurality of inlet orifices 54 on each side thereof in communication with the channels 31a. The outlet conduit has, at the lower end-portion thereof a plurality of outlet orifices 56 on each side thereof also in communication with the channels 31a. The inlet conduit 53 and the outlet conduit 55 may communicate with a common pocket in the end of the syringe 52 irrespective of whether they are also in communication with the channel or channels 31a. The principle or mode of operation is the same through the pocket as thru the channel or channels, since the inlet and outlet conduits communicate with the same pocket or the same channel or channels. The principle of feeding and withdrawing fluids is identical to that of the syringe assembly 16. The upper or open end of the syringe 52 may be oval in which case, it is connected by a slip-joint to the cross-head fitting 57, but if the top end is round it may be connected screw-threadedly. The cross-head fitting 57 has an inlet conduit 58 passing therethrough and registering with the conduit 53. This fitting 57 is in the form of a T, to provide a horizontal transparent shank 34, affording a means to focalize the syringe in a cavity or lesion and a means for visual observation of the withdrawing fluids passing therethrough. An outlet conduit 59 extends through the shank 34 and the connecting portion of the fitting 57 and registers with the outlet conduit 55 of the syringe 52.

The fluid feeding system 70, as shown in Figure 10, comprises the receptacle 35 in Figure 10 and a reservoir 38 in Figure 1, for therapeutic feeding solutions. The reservoir 38 is here shown combined with the reservoir 39 for suction inducing hydrant liquid in the double receptacle 35. The reservoirs thereof 38 and 39 are orificial in the top thereof (not shown). The feeding reservoirs 38 in Figure 1, and 35 in Figure 10 are respectively provided with an outlet 40 and 42a at the bottom thereof. In the Figures 1 and 10, a hose conduit 42 or 42a connects the outlets 40 or 40a with the inlet conduits of the fittings 18 and 57 respectively. A valve 37 or 37a associated with the conduit 42 or 42a controls respectively the flow of the solution therethrough.

In the fluid withdrawing system 71, in the Figure 10, is a centrifugal suction pump 60, communicating, through the hose conduit 47a.

In the Figure 1 is illustrated a suction-producing fitting 15, in place of the centrifugal pump 60. This fitting, 15, includes a primary tube 48 and an entrant tube 49, which is provided with a Venturi suction end 51, disposed concentrically in the primary tube 48. The fluid withdrawing tube 49 is connected to a suction hose conduit 47 at the connecting end 50, and the conduit 47 is connected to the suction handle 34a. The valve 46 is closed when it is desired to inflate the abdomen through a surgical opening therein, and

opened to release the inflation. The hydrant hose conduit 43 communicates the suction producing artifice 15 with the hydrant reservoir 39 at the outlet 41. The valve 45 controls the flow of the hydrant fluid through the hose conduit 43.

In the operation of the appliance, the fluid feeding system 70, shown in Figures 1 and 10, is elevated well above the horizontal plane of the two-way artifice 16 for the purpose of producing a gravitational flow of the therapeutic solution from the reservoir 38, Figure 1, or reservoir 35, Figure 10.

The fluid withdrawing or suctioning system 71, shown in Figures 1 and 10, is disposed below the horizontal plane of the artifice 16, that is, the horizontal plane of the lesion or cavity treated, to effectively suction, with the aid of gravity, the outcoming fluids.

First, all the valves 37-45-46 are closed, then the therapeutic solution is poured into reservoir 38 in Figure 1 or 35 in Figure 10. In Figure 1, which shows a receptacle hydrant, the suction producing liquid is poured into reservoir 39.

The apparatus is now ready to function, and it shall be operated according to what it is to do. If the treatment is to be compound, that is, if there are foreign fluids such as hemorrhages and the like first to withdraw or suction out, and subsequently a flushing out therapy is to be applied, then the procedure is this:

The syringe 17 of the two-way artifice 16 is inserted into the surgical lesion or non-surgical cavity to be treated, focalized, of course, to the best of the ability of the operator. The valves 45 and 46 are opened in Figure 1, or valve 46a in Figure 10, and an electrical switch (not shown) associated with the centrifugal pump 60 closed to start the pump. In the withdrawing system in Figure 1, the hydrant fluid flows from the reservoir 39, through the hose conduit 43, the tube conduit 48, and out to drain 44. As the hydrant fluid flows eccentrically around the Venturi end 51 of the suction tube 49, a vacuum is created there, inducing a syphonic flow of the hemorrhage from the cavity, the hemorrhage collecting in the channels 31, suctionally entering the outlet orifices 26, the outlet conduit 25, the outlet tube 33, the outlet hose conduit 47, the outlet tube conduit 49, and from the Venturi end of tube 49 carried away to drain 44 by the hydrant fluid flowing through tube 48. When the outcoming flow of the withdrawal fluid through the transparent handle 34 or 34a indicates that the hemorrhage has all been withdrawn and that only processed air is coming through the transparent handle 34 or 34a, forced by atmospheric pressure through the air processor 34, the bulb and connections 62, hose conduit 42, conduit tube 32, conduits 28, inlet orifices 30 and channels 31 or 31a, from which it follows the same course as did the outcoming hemorrhage, then the process of flushing, disinfecting, and aerating is begun by the opening of additional valve 37-37a in either Figure 1 or 10, and starting the flow of the therapeutic solution from either reservoir 38 or 35 respectively, through hose conduit 42 or 42a, tube conduit 32 or 58, inlet conduits 28, or 53, inlet orifices 30 or 54, channels 31, or 31a wherein the flushing, disinfecting and aerating of the tissues facing the channels 31 or 31a is performed and the flush withdrawn in the same sequence as the processed air aforescribed. If inflation of the cavity with processed air is desired, the valve 37 or 37a is closed after all the fluids shall have been withdrawn and the bulb at 62 com-

pressibly actuated after valve 46 or 46a is closed.

The centrifugal pump 60 is one substitute for the gravitational hydrant fluid system shown in Figure 1, a reservoir 39, conduit 43 and suction fitting 15; but a faucet hydrant is generally more convenient and satisfactory than either of the aforementioned systems. The faucet hydrant substitutes the reservoir 39 and operates cooperatively with the suction fitting 15.

It might be stated that the function of the valve 46 or 46a is to close the conduit 41 or 41a only when the apparatus is used to perform the function of inflation by manually actuating the bulb at 62, and again opened to release the inflation.

It is to be understood that preferred forms of my invention are herein shown and described; but that various changes in shape, size and arrangement of parts may be resorted to without departing from the spirit of my invention or the scope of the appended claims.

What I claim is:

1. In a therapeutic apparatus of the class described, wherein a fluid feeding means cooperates with the fluid feeding conduit of a two-way cross-head fitting provided with a two-way syringe, the combination of an air processing means communicating with the feeding conduit of the cross-head fitting, providing processed air under atmospheric pressure, and comprising the combination and arrangement of: a case having an air-intake end and a processed air-discharge end, which is provided with a chamber having an air outlet, to receive and to discharge the processed air; an air filtering means in the intake end of the case; at least three different odor or gas absorb and adsorb chemical agents arranged in series subjacent to the air filtering means to deodorize the filtered air, each of said chemical agents being adapted to permit the passing of air therethrough and to absorb and adsorb specific gases or odors more effectively; a means disposed subjacent to the chemical agents and adapted to be impregnated with therapeutical ingredients to fumigate the filtered and deodorized air and adapted to postfilter the oxides of the chemical agents, therefrom.

2. In a therapeutic apparatus of the class described, wherein a fluid feeding means cooperates with the fluid feeding conduit of a two-way cross-head fitting provided with a two-way syringe, the combination of an air processing means associated with an air compression means including a resilient air bulb having a separate air-check in the air-intake and air-discharge ends thereof, and together therewith communicating with the fluid feeding conduit of the two-way cross-head fitting provided with a two-way syringe, and normally providing processed air under atmospheric pressure, or by manipulation of the bulb of the compression means into a bodily lesion or cavity thru the feeding conduits of said cross-head fitting and syringe, said air-checks opening in the direction of the flow of the air, and closing, if the flow be reversed, the air-check in the air-intake end closing and the air-check in the air-discharge and thereof opening, when the bulb is manually compressed, said air processing means comprising the combination and arrangement of: a case having an air-intake end and a processed air-discharge end, which is provided with a chamber having an air outlet, to receive and to discharge the processed air; an air filtering means in the intake end of the case; at least three different odor absorbing and adsorbing chemical agents arranged in series sub-

ja cent to the air filtering means to deodorize the filtered air, each of said chemical agents being adapted to permit the passing of air therethrough and to absorb and adsorb specific gases or odors more effectively; a means disposed subjacent to the chemical agents and impregnated with therapeutical ingredients to fumigate the filtered and deodorized air and adapted to postfilter the oxides of the chemical agents, therefrom.

3. In a therapeutic apparatus of the class described, wherein a fluid feeding means cooperates with the fluid feeding conduit of a two-way cross-head fitting provided with a two-way syringe, the combination of an air processing means communicating with the feeding conduit of the cross-head fitting, providing processed air under atmospheric pressure, and comprising the combination and arrangement of: a case having an air-intake end and a processed air-discharge end, which is provided with a chamber having an air outlet, to receive and to discharge the processed air; an air filtering means in the intake end of the case; at least five different odor or gas absorb and adsorb chemical agents arranged in series subjacent to the air filtering means to deodorize the filtered air, each of said chemical agents being adapted to permit the passing of air therethrough and to absorb and adsorb specific gases or odors more effectively; a means disposed subjacent to the chemical agents and adapted to be impregnated with therapeutical ingredients to fumigate the filtered and deodorized air and adapted to postfilter the oxides of the chemical agents, therefrom.

4. In a therapeutic apparatus of the class described, wherein a fluid feeding means cooperates with the fluid feeding conduit of a two-way cross-head fitting provided with a two-way syringe, the combination of an air processing means associated with an air compression means including a resilient air bulb having a separate air-check in the air-intake and air-discharge ends thereof, and together therewith communicating with the fluid feeding conduit of the two-way cross-head fitting provided with a two-way syringe, and normally providing processed air under atmospheric pressure, or by manipulation of the bulb of the compression means into a bodily lesion or cavity thru the feeding conduits of said cross-head fitting and syringe, said air-checks opening in the direction of the flow of the air, and closing, if the flow be reversed, the air-check in the air-intake end closing and the air-check in the air-discharge end thereof opening, when the bulb is manually compressed, said air processing means comprising the combination and arrangement of: a case having an air-intake end and a processed air-discharge end, which is provided with a chamber having an air outlet, to receive and to discharge the processed air; an air filtering means in the intake end of the case; at least five different odor absorb and adsorbing chemical agents arranged in series subjacent to the air filtering means to deodorize the filtered air, each of said chemical agents being adapted to permit the passing of air therethrough and to absorb and adsorb specific gases or odors more effectively; a means disposed subjacent to the chemical agents and impregnated with therapeutical ingredients to fumigate the filtered and deodorized air and adapted to postfilter the oxides of the chemical agents, therefrom.

5. A therapeutic apparatus for treating diseased body lesions or cavities by feeding fluids into, and/or simultaneously withdrawing fluids

from such lesions or cavities, comprising the combination and arrangement of a two-way fluid feeding and fluid withdrawing syringe; a two-way fluid feeding and fluid withdrawing cross-head fitting, detachably connected to said syringe; fluid feeding system means in communication with the fluid feeding conduit of the cross-head fitting and the syringe; fluid withdrawing system means in communication with the fluid withdrawing conduit of the cross-head fitting and the syringe; an air processing means in communication with the feeding conduit of the cross-head fitting and the syringe and providing processed air under atmospheric pressure.

15 6. A therapeutic apparatus of the class described comprising the combination and arrangement of a two-way fluid feeding and fluid withdrawing syringe; a two-way fluid feeding and fluid withdrawing cross-head fitting, detachably connected to said syringe; fluid feeding system means in communication with the fluid feeding conduit of the cross-head fitting and the syringe; fluid withdrawing system means in communication with the fluid withdrawing conduit of the cross-head fitting and the syringe; an air processing means in communication with the feeding conduit of the cross-head fitting and the syringe; an air compression means associated with said air processing means and including a resilient air bulb having a separate air-check in the air-intake and air-discharge ends thereof, and together therewith communicating with the fluid feeding conduit of the two-way cross-head fitting provided with a two-way syringe and normally providing processed air under atmospheric pressure, or by manipulation of the bulb of the compression means into a bodily lesion or cavity thru the feeding conduits of said cross-head fitting and syringe, said air-checks opening in the direction of the flow of the air, and closing if the flow be reversed, the air-check in the air-intake end closing and the air-check in the air-discharge end thereof opening, when the bulb is manually compressed.

45 7. A therapeutic apparatus for treating diseased body lesions or cavities by feeding fluids into, and/or simultaneously withdrawing fluids from such lesions or cavities, comprising the combination and arrangement of a two-way fluid feeding and fluid withdrawing syringe; a two-way fluid feeding and fluid withdrawing cross-head fitting, detachably connected to said syringe; fluid feeding system means in communication with the fluid feeding conduit of the cross-head fitting and the syringe; fluid withdrawing system means in communication with the fluid withdrawing conduit of the cross-head fitting and the syringe; an air processing means in communication with the feeding conduit of the cross-head fitting and the syringe and providing processed air under atmospheric pressure; said air processing means comprising the combination and arrangement of a case having an air-intake end and a processed air-discharge end, which is provided with a chamber having an air outlet, to receive and to discharge the processed air; an air filtering means in the intake end of the case; at least three different odor or gas absorb and adsorb chemical agents arranged in series subjacent to the air filtering means to deodorize the filtered air, each of said chemical agents being adapted to permit the passing of air therethrough and to absorb and adsorb specified gases or odors more effectively; a means disposed subjacent to the chemical agents and impregnated

with therapeutic ingredients to fumigate the filtered and deodorized air and adapted to post filter the oxides of the chemical agents, therefrom.

8. A therapeutic apparatus for treating diseased body lesions or cavities by feeding fluids into, and/or simultaneously withdrawing fluids from such lesions or cavities, comprising the combination and arrangement of a two-way fluid feeding and fluid withdrawing syringe; a two-way fluid feeding and fluid withdrawing cross-head fitting, detachably connected to said syringe; fluid feeding system means in communication with the fluid feeding conduit of the cross-head fitting and the syringe; fluid withdrawing system means in communication with the fluid withdrawing conduit of the cross-head fitting and the syringe; an air processing means in communication with the feeding conduit of the cross-head fitting and the syringe and providing processed air under atmospheric pressure; said air processing means comprising the combination and arrangement of a case having an air-intake end and a processed air-discharge end, which is provided with a chamber having an air outlet, to receive and to discharge the processed air; an air filtering means in the intake end of the case; at least three different odor or gas absorb and adsorb chemical agents arranged in series subjacent to the air filtering means to deodorize the filtered air, each of said chemical agents being adapted to permit the passing of air therethrough and to absorb and adsorb specified gases or odors more effectively; a means disposed subjacent to the chemical agents and impregnated with therapeutic ingredients to fumigate the filtered and deodorized air and adapted to postfilter the oxides of the chemical agents therefrom.

9. A therapeutic apparatus of the class described comprising the combination and arrangement of a two-way fluid feeding and fluid withdrawing syringe; a two-way fluid feeding and fluid withdrawing cross-head fitting, detachably connected to said syringe; fluid feeding system means in communication with the fluid feeding conduit of the cross-head fitting and the syringe; fluid withdrawing system means in communication with the fluid withdrawing conduit of the cross-head fitting and the syringe; an air processing means in communication with the feeding conduit of the cross-head fitting and the syringe; an air compression means associated with said air processing means and including a resilient air bulb having a separate air-check in the air-intake and air-discharge ends thereof, and together therewithal communicating with the fluid feeding conduit of the two-way cross-head fitting provided with a two-way syringe and normally providing processed air under atmospheric pressure, which may be compressed into a bodily lesion or cavity thru the feeding conduits of said cross-head fitting and syringe, by repeated manual compression of the bulb, said air-checks opening in the direction of the flow of the air, and closing if the flow be reversed; the air-check in the air-intake end closing and the air-check in the air-discharge end thereof opening, when the bulb is manually compressed; said air processing means comprising the combination and arrangement of a case having an air-intake end and a processed air-discharge end, which is provided with a chamber having an air outlet, to receive and to discharge the processed air; an air filtering means in the intake end of the case; at least three

different odor or gas absorb and adsorbing chemical agents arranged in series subjacent to the air filtering means to deodorize the filtered air, each of said chemical agents being adapted to permit the passing of air therethrough and to absorb and adsorb specific gases or odors more effectively; a means disposed subjacent to the chemical agents and adapted to be impregnated with therapeutic ingredients to fumigate the filtered and deodorized air and adapted to postfilter the oxides of the chemical agents, therefrom.

10. In a therapeutic apparatus of the class described, wherein a fluid feeding means cooperates with the fluid feeding conduit of a two-way cross-head fitting provided with a two-way syringe, the combination of an air processing means communicating with the feeding conduit of the cross-head fitting, providing processed air under atmospheric pressure, and comprising the combination and arrangement of: a case having an air intake end and a processed air discharge end, which is provided with a chamber having an air outlet, to receive and to discharge the processed air; an air filtering means in the intake end of the case; at most two different odor absorb and adsorb chemical agents arranged in series subjacent to the air filtering means to deodorize the filtered air, each of said chemical agents being adapted to permit the passing of air therethrough and to absorb and adsorb specific gases or odors more effectively; a means disposed subjacent to the chemical agents and adapted to be impregnated with therapeutic ingredients to fumigate the filtered and deodorized air and adapted to postfilter the oxides of the chemical agents, therefrom.

11. In a therapeutic apparatus of the class described, wherein a fluid feeding means cooperates with the fluid feeding conduit of a two-way cross-head fitting provided with a two-way syringe, the combination of an air processing means associated with an air compression means including a resilient air bulb having a separate air-check in the air-intake and air-discharge ends thereof, and together therewithal communicating with the fluid feeding conduit of the two-way cross-head fitting provided with a two-way syringe and normally providing processed air under atmospheric pressure, or by manipulation of the bulb of the compression means into a bodily lesion or cavity thru the feeding conduits of said cross-head fitting and syringe, said air-checks opening in the direction of the flow of the air, and closing if the flow be reversed; the air-check in the air-intake end closing and the air-check in the air-discharge end thereof opening, when the bulb is manually compressed; said air processing means comprising the combination and arrangement of a case having an air-intake end and a processed air-discharge end, which is provided with a chamber having an air outlet, to receive and to discharge the processed air; an air filtering means in the intake end of the case; at most two different odor or gas absorb and adsorb chemical agents arranged in series subjacent to the air filtering means to deodorize the filtered air, each of said chemical agents being adapted to permit the passing of air therethrough and to absorb and adsorb specific gases or odors more effectively; a means disposed subjacent to the chemical agents and adapted to be impregnated with therapeutic ingredients to fumigate the filtered and deodorized air and adapted to postfilter the oxides of the chemical agents, therefrom.

12. A therapeutic apparatus for treating diseased body lesions or cavities by feeding fluids into, and/or simultaneously withdrawing fluids from such lesions or cavities, comprising the combination and arrangement of a two-way fluid feeding and fluid withdrawing syringe; a two-way fluid feeding and fluid withdrawing cross-head fitting, detachably connected to said syringe; fluid feeding system means in communication with the fluid feeding conduit of the cross-head fitting and the syringe; fluid withdrawing system means in communication with the fluid withdrawing conduit of the cross-head fitting and the syringe; an air processing means in communication with the feeding conduit of the cross-head fitting and the syringe and providing processed air under atmospheric pressure; said air processing means comprising the combination and arrangement of a case having an air-intake end and a processed air-discharge end, which is provided with a chamber having an air outlet, to receive and to discharge the processed air; and air filtering means in the intake end of the case; at least five different odor or gas absorb and adsorb chemical agents arranged in series subjacent to the air filtering means to deodorize the filtered air, each of said chemical agents being adapted to permit the passing of air therethrough and to absorb and adsorb specified gases or odors more effectively; a means disposed subjacent to the chemical agents and impregnated with therapeutical ingredients to fumigate the filtered and deodorized air and adapted to postfilter the oxides of the chemical agents therefrom.

13. A therapeutic apparatus for treating diseased body lesions or cavities by feeding fluids into, and/or simultaneously withdrawing fluids from such lesions or cavities, comprising the combination and arrangement of a two-way fluid feeding and fluid withdrawing syringe; a two-way fluid feeding and fluid withdrawing cross-head fitting, detachably connected to said syringe; fluid feeding system means in communication with the fluid feeding conduit of the cross-head fitting and the syringe; fluid withdrawing system means in communication with the fluid withdrawing conduit of the cross-head fitting and the syringe; an air processing means in communication with the feeding conduit of the cross-head fitting and the syringe and providing processed air under atmospheric pressure; said air processing means comprising the combination and arrangement of a case having an air-intake end and a processed air-discharge end, which is provided with a chamber having an air outlet, to receive and to discharge the processed air; an air filtering means in the intake end of the case; at most two different odor or gas absorb and adsorb chemical agents arranged in series subjacent to the air filtering means to deodorize the filtered air, each of said chemical agents being adapted to permit the passing of air therethrough and to absorb and adsorb specified gases or odors more effectively; a means disposed subjacent to the chemical agents and impregnated with therapeutical ingredients to fumigate the filtered and deodorized air and adapted to postfilter the oxides of the chemical agents therefrom.

14. A therapeutic apparatus of the class described comprising the combination and arrangement of a two-way fluid feeding and fluid withdrawing syringe; a two-way fluid feeding and fluid withdrawing cross-head fitting, detachably connected to said syringe; fluid feeding system means in communication with the fluid feeding

conduit of the cross-head fitting and the syringe; fluid withdrawing system means in communication with the fluid withdrawing conduit of the cross-head fitting and the syringe; an air processing means in communication with the feeding conduit of the cross-head fitting and the syringe; an air compression means associated with said air processing means and including a resilient air bulb having a separate air-check in the air-intake and air-discharge ends thereof, and together therewithal communicating with the fluid feeding conduit of the two-way cross-head fitting provided with a two-way syringe and normally providing processed air under atmospheric pressure, or by manipulation of the bulb of the compression means into a bodily lesion or cavity thru the feeding conduits of said cross-head fitting and syringe, said air-checks opening in the direction of the flow of the air, and closing, if the flow be reversed, the air-check in the air-intake end closing and the air-check in the air-discharge end thereof opening, when the bulb is manually compressed; said air processing means comprising the combination and arrangement of a case having an air-intake end and a processed air-discharge end, which is provided with a chamber having an air outlet, to receive and to discharge the processed air; an air filtering means in the intake end of the case; at least five different odor or gas absorb and adsorbing chemical agents arranged in series subjacent to the air filtering means to deodorize the filtered air, each of said chemical agents being adapted to permit the passing of air therethrough and to absorb and adsorb specific gases or odors more effectively; a means disposed subjacent to the chemical agents and adapted to be impregnated with therapeutical ingredients to fumigate the filtered and deodorized air and adapted to postfilter the oxides of the chemical agents, therefrom.

15. A therapeutic apparatus of the class described comprising the combination and arrangement of a two-way fluid feeding and fluid withdrawing syringe; a two-way fluid feeding and fluid withdrawing cross-head fitting, detachably connected to said syringe; fluid feeding system means in communication with the fluid feeding conduit of the cross-head fitting and the syringe; fluid withdrawing system means in communication with the fluid withdrawing conduit of the cross-head fitting and the syringe; an air processing means in communication with the feeding conduit of the cross-head fitting and the syringe; an air compression means associated with said air processing means and including a resilient air bulb having a separate air-check in the air-intake and air-discharge ends thereof, and together therewithal communicating with the fluid feeding conduit of the two-way cross-head fitting provided with a two-way syringe and normally providing processed air under atmospheric pressure, or by manipulation of the bulb of the compression means into a bodily lesion or cavity thru the feeding conduits of said cross-head fitting and syringe, said air-checks opening in the direction of the flow of the air, and closing if the flow be reversed, the air-check in the air-intake end closing and the air-check in the air-discharge end thereof opening, when the bulb is manually compressed; said air processing means comprising the combination and arrangement of a case having an air-intake end and a processed air-discharge end, which is provided with a chamber having an air outlet, to receive and to discharge the processed air; an air filtering means in the

intake end of the case; at most two different odor or gas absorb and adsorbing chemical agents arranged in series subjacent to the air filtering means to deodorize the filtered air; each of said chemical agents being adapted to permit the passing of air therethrough and to absorb and adsorb specific gases or odors more effectively; a means disposed subjacent to the chemical agents and adapted to be impregnated with therapeutic ingredients to fumigate the filtered and deodorized air and adapted to postfilter the oxides of the chemical agents, therefrom.

16. In a syringe of the class described, an elongated cylindrical body having a plurality of longitudinally extending and alternating parallel channels and ridges; an inlet conduit extending longitudinally in each ridge, each inlet conduit having an open top end; at least one separate group of plurality of outlets in each ridge communicating each inlet conduit with at least one adjoining channel; an outlet conduit in the body parallel to and surrounded by the channels and ridges, said outlet conduit having an open top end; a separate plurality of inlets in the body communicating said outlet conduit with each channel.

17. In a therapeutic appliance of the class described, a two-way syringe comprising an elongated cylinder-like body-portion having a connecting end and separate pluralities of radially alternating corrugations and channels extending parallelly and longitudinally therein, and defining the surface thereof; a tubular inlet conduit extending longitudinally in each corrugation emerging in the connecting end and having a closed lower end; a tubular outlet conduit disposed longitudinally and axially in the body-portion emerging in the connecting end thereof and having a closed lower end; a plurality of orifices communicating each inlet conduit with at least one of the two channels astride each corrugation; and a separate plurality of orifices communicating the outlet conduit with each channel.

18. The structure defined in claim 17 in which the body-portion has, in addition, an orifice in the lower end thereof communicating with the outlet conduit.

19. The structure defined in claim 17 in which the body-portion is provided with a plurality of webs spaced apart in each channel and integral with the surface of the body-portion, each forming a pocket; a separate orifice communicating the outlet conduit with each pocket; one or more orifices communicating at least one of the two inlet conduits astride each pocket, with the same pocket.

20. In a therapeutic appliance of the class described, the combination and arrangement of a two-way syringe and a two-way cross-head fitting detachably attached to the syringe, said syringe comprising an elongated cylinder-like body-portion having a connecting end and separate pluralities of radially alternating corrugations and channels extending parallelly and longitudinally therein and defining the surface thereof; a tubular inlet conduit extending longitudinally in each corrugation emerging in the connecting end and having a closed lower end; a tubular outlet conduit disposed longitudinally and axially in the body portion emerging in the connecting end thereof and having a closed lower end; a plurality of orifices communicating each inlet conduit with at least one of the two channels astride each corrugation; a separate plurality of orifices communicating the outlet conduit with each channel;

and said cross-head fitting comprising a body-portion including an inlet tubular conduit communicating with all the inlet conduits in the body-portion, said inlet conduit having an entrant outlet conduit communicating with the outlet conduit in the body-portion and said entrant outlet conduit having a transparent shank adapted to be held in the palm of the hand; whereby maneuverably to apply to, and focalize the syringe of the combination in a bodily lesion or cavity, and whereby to observe the pathological peculiarities of the bodily secretions or fluids as same flow therethrough in the withdrawal thereof.

21. In a therapeutic appliance of the class described for use in combination with a suction means and a fluid supply means, a detachably combined two-way nozzle and a two-way cross-head fitting; said two-way nozzle comprising a slender body portion having an end adapted for detachable connection to said two-way cross-head fitting, an inlet conduit and an outlet conduit extending parallel from the detachable end throughout the major part of the body portion, each conduit having an orifice in said detachable end, a channel formed longitudinally in the outer surface of the body-portion on one side thereof medially between the conduits, a plurality of orifices leading from the inlet conduit to the channel, and a plurality of orifices leading from said channel to the outlet conduit; and said two-way cross-head fitting having separate inlet and outlet conduits extending therethrough and communicating with the corresponding conduits of the nozzle, said outlet conduit emerging from the fitting in the form of a transparent tubular shank adapted to communicate with the suction means, and serving as a handle whereby to apply the nozzle to a bodily lesion, or cavity, and as means for observing the fluids as same are being withdrawn through said transparent shank; and said inlet conduit being adapted to communicate with the fluid supply means.

22. The structure defined in claim 21, in which the body-portion has a channel formed longitudinally in the surface of said body-portion on both sides thereof medially between the conduits.

23. In a therapeutic appliance of the class described, a two-way nozzle comprising an elongated slender body-portion, an inlet conduit and an outlet conduit extending in parallel relationship with the body from one end throughout the major part of the body portion, one or more pockets formed in the outer surface of the body-portion, a separate orifice leading through the body portion from the inlet conduit to a point on said surface adjacent to each of said one or more pockets, and a separate orifice leading from each of said one or more pockets to the outlet conduit.

24. In a therapeutic appliance of the class described for use in conjunction with a suction means and a fluid supply means, a detachably combined two-way nozzle and a two-way cross-head fitting, said two-way nozzle comprising a slender body-portion having an end adapted for detachable connection to said two-way cross-head fitting, an inlet conduit and an outlet conduit extending adjacently in the body-portion from the lower end thereof, each conduit having an orifice in the detachable end, one or more pockets formed in the outer surface of the body-portion, a separate orifice leading through said body portion from the inlet conduit to a point on the body-portion outer surface adjacent to a

separate orifice leading from each of said one or more pockets to the outlet conduit; said two-way cross-head fitting having separate inlet and outlet conduits extending therethrough and communicating with the corresponding conduits of the nozzle, said outlet conduit emerging in the form of a transparent tubular shank adapted to communicate with the suction means, and serving as a handle whereby to apply the nozzle to a bodily lesion, or cavity, and as means for observing the fluids as same are being withdrawn through said transparent shank, and said inlet conduit being adapted to communicate with the fluid supply means.

25. In a device of the class described for use in combination with a suction means having a suction conduit and a fluid supply means, a detachably combined elongated two-way nozzle and a two-way cross-head fitting, said nozzle having inlet conduit means and outlet conduit means extending within the nozzle and in parallel relation with each other throughout the major portion thereof, said fitting being detachably connected to one end of said nozzle, said inlet conduit means and said outlet conduit means having orifices in said detachable end, depression means in the surface of the nozzle; orificial means leading from the inlet conduit means to the depression means; and orificial means leading from the depression means to the outlet conduit means; and said two-way cross-head fitting including inlet conduit communicating with the inlet conduit means of the nozzle, outlet conduit communicating with the outlet conduit means of the nozzle, said outlet conduit of the fitting emerging in the form of a transparent tubular shank, adapted to communicate with the suction conduit of a suction means, and adapted to be held in the palm of the hand to apply the nozzle to bodily lesions, or cavities, and to focalize said nozzle therein, and adapted for visually observing the bodily secretions for pathological peculiarities as same are being suctioned through said transparent shank while said shank is being held in the hand, and said inlet conduit being adapted to communicate with a fluid supply means.

26. In a therapeutic appliance of the class described, the combination and arrangement of a two-way-syringe and a two-way cross-head fitting detachably attached to the syringe, said syringe comprising an elongated cylinder-like body-portion having a connecting end and separate pluralities of radially alternating corrugations and channels extending parallelly and longitudinally therein and defining the surface thereof; a tubular inlet conduit extending longitudinally in each corrugation emerging in the connecting end and having a closed lower end; a tubular outlet conduit disposed longitudinally and axially in the body portion emerging in the connecting end thereof and having a closed lower end; a plurality of orifices communicating each inlet conduit with at least one of the two channels astride each corrugation; a separate plurality of orifices communicating the outlet conduit with each channel; and said cross-head fitting comprising a body-portion including an inlet tubular conduit communicating with all the inlet conduits in the body-portion, said inlet conduit having an entrant outlet conduit communicating with the outlet conduit in the body-portion and said entrant outlet conduit having a transparent shank adapted to be held in the palm of the hand; whereby maneuverably to apply to, and focalize the syringe of the combination in

a bodily lesion or cavity, and whereby to observe the pathological peculiarities of the bodily secretions or fluids as same flow therethrough in the withdrawal thereof, each said channel having a plurality of spaced apart webs therein integral with the surface of the body-portion and forming pockets; at least one orifice communicating each pocket with at least one of the two inlet conduits provided astride each pocket and a separate orifice communicating the outlet conduit with each pocket.

27. In a device of the class described for use in conjunction with a suction means and a fluid supply means, a detachably combined elongated two-way nozzle and a two-way cross-head fitting, said nozzle having a plurality of angularly spaced longitudinally extending inlet conduits and longitudinally extending channels extending in the outer surface of the nozzle between each two adjacent inlet conduits; an axially concentric outlet conduit, each inlet conduit and said outlet conduit extending from end to end of the nozzle, one end of said nozzle being detachably combined with the cross-head fitting; a plurality of orifices leading from at least one of each two inlet conduits adjacent each channel; a separate plurality of orifices leading from each channel to the outlet conduit; and said two-way cross-head fitting having an inlet conduit adapted to communicate with all the inlet conduits of the nozzle and with the fluid supply means at the upper end thereof, and an entrant outlet conduit adapted to communicate with the outlet conduit of the nozzle, said entrant outlet conduit emerging from the fitting in the form of a transparent tubular shank adapted to communicate with the suction conduit of the suction means, said shank being adapted to be held in the palm of the hand to apply the nozzle to bodily lesions, or cavities, and to focalize said nozzle therein, and adapted for visually observing the bodily secretions for pathological peculiarities as same are being suctioned through said transparent shank, while said shank is being held in the hand.

28. In a device of the class described, in combination, a two-way cross head fitting containing an inlet passage which at one end is adapted for connection to a fluid supply and an outlet passage which at one end is adapted for connection to a source of fluid suction, both of said passages terminating in a common outlet end of the fitting, and a two-way nozzle consisting of a slender linear body containing inlet and outlet passages extending parallel throughout the major portion of the body, means on one end of the nozzle cooperable with the outlet end of the cross head fitting for detachably connecting the same to the cross head fitting whereby the inlet and outlet passages in the nozzle are in communication with the inlet and outlet passages in the cross head fitting, said nozzle having a first orifice extending transversely through a portion of the nozzle into the inlet passage to permit egress of fluid from the inlet passage to a body cavity, a recess formed in the outer surface of the nozzle for collecting fluid from the body cavity, and a second orifice extending through a portion of the nozzle and connecting the interior of the recess with the outlet passage for conducting fluid from the recess to the outlet passage.

29. In a device of the class described, a two-way nozzle consisting of a slender linear body of substantially uniform diameter throughout

the linear limits thereof, longitudinally extending inlet and outlet passages formed within the interior of the body and extending parallel throughout the major portion of the body, a first orifice extending laterally through a portion of the body and into the inlet passage and adapted to permit the egress of fluid from the inlet passage, a recess formed in the outer surface of the body for collecting fluid, a second orifice extending laterally through a portion of the body and connecting the interior of the recess with the outlet passage, and means united with one end of the nozzle for detachably connecting the same to a common end of a cross head fitting.
